CLAIM

The ornamental design for a candelabra base socket assembly, as shown and described.

DESCRIPTION

FIG. 1 is a front elevational view of a candelabra base socket assembly showing my design;

FIG. 2 is a perspective view thereof;

FIG. 3 is a bottom plan view thereof;

FIG. 4 is a front elevational view of a second embodiment of a candelabra base socket assembly showing my design;

FIG. 5 is a perspective view thereof; and,

FIG. 6 is a bottom plan view thereof.

The top of the candelabra base socket assembly is unornamented and not visible in normal use, since it is mounted against a base plate of a ceiling mounted luminaire. Therefore, the top of the candelabra base socket assembly forms no part of the claimed design, and the top plan view has been omitted.

The broken line showing of the other luminaire elements and lamps in the Figures is for illustrative purposes only and forms no part of the claimed design.
